UNITED STATES PATENT OFFICE.

EMIDIO IANNI, OF NEW DERRY, PENNSYLVANIA.

RAIL JOINT.

Application filed March 30, 1923. Serial No. 628,836.

To all whom it may concern:

Be it known that I, EMIDIO IANNI, a citizen of Italy, residing at New Derry, in the county of Westmoreland and State of Pennsylvania, have invented new and useful Improvements in Rail Joints, of which the following is a specification.

The object of this invention is to provide a particular type of interlocking rail joint, by the use of which fish plates and bolts may be dispensed with.

A further object is to provide abutting rail ends with interlocking tongues constructed to permit of removal and replacement of a worn or broken rail by merely loosening spikes at the point of juncture of the defective rail with the adjacent rails.

A still further object is to provide abutting rail ends with tongues and cutaway portions having curved surfaces, and reversely arranged, certain of the ends having web portions between the reversely arranged tongues.

With the foregoing and other objects in view, the invention consists in the novel construction and arrangement of elements described and claimed, it being understood that modifications may be made within the scope of the claims without departing from the spirit of the invention.

In the drawings, Figure 1 is a perspective view showing abutting rail ends in contact; Figure 2 is a top plan view, with the rail ends separated; Figure 3 is a side elevation, the ends being separated; Figure 4 is a vertical section on line 4—4 of Figure 3; Figures 5 and 6 are end views showing respectively the horizontal opening and the horizontal web received by the opening.

The abutting rails of a track are designated 10 and 12, and rail 10 is provided with longitudinally extending tongues 14 and 15, each having concave and convex surfaces 16' and 16, the curves of the respective tongues extending in opposite directions.

The tongues of the respective rail ends are in diagonally opposed relation,—tongue 15 formed as in Figure 1, for instance, extending into a correspondingly formed recess of the abutting rail, the recess terminating in an approximately central horizontal plane,

as shown. Tongue 14 of Figure 2 enters a recess at the base of rail 12, one wall of the recess being dotted at 20, in that view.

The abutting rail is provided with 55 tongues 18 and 19, each having a surface 20 in the form of a compound curve, for cooperation with surfaces 16, 16' of the adjacent rail. This arrangement facilitates the disengagement of the rails when a sufficient 60 number of spikes are removed to permit of the separation of abutting rails at the joint.

An important feature of the construction is horizontal web 17 which fits between 65 tongues 14 and 15 and acts as a guiding element during the swinging movement at the joint, so that the rail ends will not bind, due to slight twisting action, after the spikes are removed.

It will be observed that the rail cannot 70 become loose as long as the spikes remain in place, and that the use of bolts, nuts, nut locks and fish plates is dispensed with.

In laying the rails, they are assembled in 75 alinement and spiked to the ties, without other securing devices, as indicated. In replacing a rail the spikes of the old rail are removed and relative angular movement in a horizontal plane is imparted to the rail ends, resulting in movement of the convex surfaces with reference to the concave surfaces, and immediate separation. The new rail is inserted by a reverse movement of a 80 similar kind, and spiked down.

What is claimed is:

1. The combination of abutting rail ends, one of the rails being formed with horizontally extending tongues, reversely arranged, and the other rail being formed with tongues arranged reversely with respect to those first named, the tongues of the respective rails being in diagonally opposed relation, and each tongue being adjacent to an outer side of the rail, and a horizontal web formed between the tongues of 90 one rail and fitting between the tongues of the abutting rail.

2. The combination of abutting rail ends, one of the rails being formed with longitudinally extending tongues reversely arranged and having engaging surfaces of 95 convex form, and the other of said rails

being formed with tongues having engaging surfaces in the form of a compound curve, for cooperation with the convex surfaces.

3. The combination of abutting rail ends, one of the rails being formed with longitudinally extending tongues reversely arranged and having engaging surfaces of convex form, and the other of said rails

being formed with tongues having engaging surfaces in the form of a compound curve, for cooperation with the convex surfaces, and a horizontal web formed on one rail end and fitting between the tongues of the abutting rail end. 10

In testimony whereof I affix my signature.
EMIDIO IANNI.
